UNITED STATES PATENT OFFICE.

EDMUND C. MORGAN, OF CHICAGO, ILLINOIS; OLIVE EUGENIE MORGAN EXECUTRIX
OF SAID EDMUND C. MORGAN, DECEASED.

MINING MACHINE.

Application filed July 6, 1914. Serial No. 849,018.

To all whom it may concern:

Be it known that I, EDMUND C. MORGAN, a citizen of the United States, residing at Chicago, in the county of Cook and State 5 of Illinois, have invented certain new and useful Improvements in Mining Machines, of which the following is a specification.

My invention relates to mining machines and has more particular reference to improvements in machines for mining coal and the like.

One of the objects of my invention is to provide an improved machine of this character which will be simple, durable and reliable in construction and effective and efficient in operation.

Another object of my invention is to provide improved cutting mechanism for use in connection with machines of the type which 20 constitutes the subject matter of my co-pending application, Serial No. 849,071, filed July 6, 1914.

Another object of my invention is to provide an improved construction of cutting 25 mechanism for machines of the type constituting the subject matter of said co-pending application whereby a plurality of blocks of coal may be simultaneously cut or severed from the vein or mass thereof.

Other objects of my invention will appear hereinafter.

Referring to the accompanying drawings:

Fig. 1 is a top plan view of an improved construction embodying my invention.

Fig. 2 is a bottom plan view of the construction shown in Fig. 1.

Fig. 3 is a longitudinal section taken on the line 3—3 of Fig. 2.

Fig. 4 is a transverse section on the line 40 4—4 of Fig. 3.

Fig. 5 is a transverse section on the line 5—5 of Fig. 3.

Fig. 6 is a transverse section on the line 6—6 of Fig. 3.

Fig. 7 is a side elevation of the forward portion of the structure shown in Fig. 3, showing the side cutting mechanism and the portion of the top cutting mechanism.

Fig. 8 is an enlarged view of a portion of 50 one of the chain cutters;

Fig. 9 is a transverse sectional view on the line 9—9 of Fig. 8 looking in the direction of the arrows;

Fig. 10 is a top plan view similar to Fig.

1, of a modified construction adapted for 55 the cutting of a plurality of blocks simultaneously.

Fig. 11 is a sectional view taken substantially transversely of Fig. 10 on the line 11—11 thereof, and

Fig. 12 is a transverse section on the line 12—12 of Fig. 10.

Fig. 13 is a rear end elevation of the supporting mechanism of the structure shown in Figs. 1, 2, 3, 4 and 5;

Fig. 14 is a transverse sectional view of the lower rear portion of the supporting frame shown in Fig. 13;

Fig. 15 is a substantially horizontal sectional plan view of the supporting structure 70 shown in Fig. 13 and of the plane kerf-cutting apparatus;

Fig. 16 is a transverse vertical section of the structure looking rearwardly;

Fig. 17 is a transverse detail section of a 75 part of the structure shown in Fig. 15, showing the driving mechanism for the plane kerf cutter;

Fig. 18 is a detail view, partly in section, showing further details of the driving mechanism for the plane kerf cutter shown in Fig. 15;

Fig. 19 shows a longitudinal sectional elevation of the structure shown in Figs. 1, 2, 3, 4 and 5, together with supporting frame 85 work therefor;

Fig. 20 is a sectional elevation of Fig. 19 on the line 20—20 looking forward in the direction of the arrows; and

Fig. 21 is a diagrammatic side elevation 90 of the apparatus shown in Fig. 19, illustrating the lower position of the cutting mechanism and of the chute in dotted lines.

In my copending application above referred to I have shown, described and 95 claimed a mining machine wherein cutting mechanism goes forward and cuts or severs a block of coal from the mass or vein thereof, and wherein the severed block is removed from its original position with respect to the vein and discharged or deposited in a chute or guiding structure out of the way of the cutting mechanism whereby said cutting mechanism will be free to cut another block thus making the machine a constantly operating one performing the functions of cutting blocks of coal and removing them in a single operation. In the

said machine, a complete understanding of which may be had by reference to said co-pending application, the cutting mechanism bodily moves in an arcuate path and the chute or receiving structure is arcuately aligned with the line of movement of the cutting mechanism. In the present invention I maintain the same principles of operation and function as involved in said co-pending application but I provide in the present case a modified form of cutting mechanism adaptable to the type of mining machine involved in said co-pending application and possessing certain features of adjustment. In the present invention I also arrange the cutting mechanism so that a plurality of blocks of coal may be simultaneously cut. In the present drawings I have merely shown and will describe sufficient structure of the machine in said co-pending application as to enable one skilled in the art to understand my present invention, and reference may be had to said co-pending application for a complete understanding of the parts of said complete machine not shown in the present drawings. Referring to Figs. 1 to 9 the curved or arcuate chute or receiving structure of said other machine is illustrated at A. This receiving chute is arcuately curved, rectangular in section, and embodies the side walls 1 and top and bottom walls 2 and 3. The forward end of the chute is open but the bottom wall (Fig. 3), as is seen, extends forward between the side cutting mechanism to a point substantially flush with the top cutting chain. Operating on each side of the chute at the forward end thereof are side cutting mechanisms B. These cutting mechanisms are bodily movable in planes substantially parallel with the side walls 1 of the chute but they move bodily in an arcuate path which is preferably substantially in arcuate alignment with the curvature of the chute A, hence they will cut parallel kerfs in the vein C of coal. Thus they define the width of the block of coal which is to be cut. Each of these side cutting mechanisms involves a flat elongated frame 4 around the periphery or edge of which a continuous loop cutting chain 5 travels. These chains may be of any suitable or standard construction and are preferably of the link construction. No further description of them is necessary except to say that they are provided with a plurality of cutting knives or bits 6 adapted to cut a kerf wide enough to admit the chain and frame 4. These cutting mechanisms are mounted upon a common frame 7 which extends across the machine beneath the chute A and is provided with depending loops 8, so to speak, at each side. This common frame 7 is simply attached by bolts 9 or otherwise, to a shiftable frame 10, but these bolts (see Figs. 2 and 6) pass through slots 11 in the frame 7 so as to permit considerable adjustment relatively to the frame 10. This adjustment is provided so that the cutting mechanisms B may be properly positioned relatively to the end of the chute and to the top cutting mechanism D. In order that the frame 7 may be conveniently moved for adjustment purposes I provide it with a depending lug 12 which carries an adjusting bolt 13. This bolt is threaded through a lug 14 on the frame 10 and a nut 15 positioned on each side of said lug for locking the parts in their adjusted position, it being understood, of course, that the lug 14 (Figs. 2, 3 and 6) passes through a suitable slot 16 to allow for said adjustment of the frame 7. The driving of the cutting chains 5 is accomplished through the medium of a transverse shaft 17 and sprockets 18 keyed on said shaft adjacent the ends thereof. The chains 5, as is clearly shown in Fig. 6, pass around these sprockets and mesh therewith whereby they are driven. The shaft 17 is journaled in bearings in the inner sides of the loop portions 8 of said frame 7 and is also journaled in bushings 19 at its outer ends. These bushings have enlarged heads (Figs. 6 and 7) which are set in correspondingly shaped sockets or bearings in the outer side portions of the loops 8 of frame 7 so that said bearings or bushings 19 may be readily rotated relatively to the loops 8 to adjust the positions of the cutter bars B. They are provided with holes 20 for engagement by a suitable tool for rotating said bearings and the bearings may be locked or fastened in any position to which they are rotated by means of set screws 21. The inner ends of the cutting mechanism frames 4 are offset laterally with respect to the main portions of said frames and are provided with elongated slots 22 (Fig. 6) through which the bearings or bushings 19 pass. These slots permit of a longitudinal adjustment of the frames 4 for the purpose of tightening or loosening the cutting chains 5 or the renewal of links in said chain.

The bushings or bearings 19 carry threaded bolts which pass through holes in the ends or cross pieces 23 of the cutting mechanism frame 5 and on each side of these cross pieces are nuts 24. The bushings 19, of course, are squared (Fig. 7) so that they will slide relatively to the frame 4. Thus the frames 4 are locked to the bushings 19 so that by rotating said bushings 19 the cutting mechanisms may be rotarily adjusted about the shaft 17 as a center, and by means of this construction the chains may also be tightened or loosened, as desired. The rotary adjustment of the cutting mechanism about the shaft 17 possesses considerable advantage with re-

spect to the cutting of the kerfs. It will be remembered that these cutting mechanisms are intended to be moved bodily in an arcuate path which is preferably aligned with the curvature of the chute A. The bodily movement of the cutting mechanism, however, need not necessarily be in an arc which is of the same radius as the arc of the chute A for the reason that the center of the arc on which the chute is disposed may be above or below the floor line of the mine. Hence, the cutting mechanism must be adjusted so that at the end of its forward stroke or cutting stroke it will occupy a position substantially parallel with the floor of the mine. This is true even if the cutting mechanism is bodily moved on an arc which has the same center as the arc on which the chute is disposed for the reason that the machine might be constructed with said two centers coincident and located above the floor of the mine as it is in the present drawings. As before stated, the cutting mechanisms through the medium of the frame 7, are mounted upon the frame 10 and by shifting this frame bodily, a bodily movement or reciprocation of the cutting mechanisms is obtained. Before describing the mechanism for driving or shifting this frame 10 I will describe the mechanisms for driving the cutting chains 5. According to Figs. 2, 3, 6 and 7, it will be seen that the shaft 17 carries a beveled gear 30 which is driven by a correspondingly beveled gear 31 on the end of a short shaft 32 which is journaled in the frame 7. Journaled in suitable bearings 33 on the frame 10 is a longitudinally disposed shaft 34 (Fig. 2) and between this shaft 34 and the short shaft 32 (Fig. 3) is a universal joint 35, one member 36 of which has an elongated squared socket. In this squared socket is a correspondingly squared shank on the end of the short shaft 32. The universal joint 35 and the extensible driving connection embodying the squared socket portion 36 and squared shank 37, constitute a completely flexible connection between the shaft 34 and the short shaft 32 which readily permits any of the above described adjustments for the cutting mechanisms to be made. A large gear 39 is loosely mounted on the shaft 34 and is driven from a small pinion 40 (Fig. 2) on the armature shaft of a suitable driving motor 41 on the frame 10. This gear 39 is adapted to be connected with or disconnected from the shaft 34 by means of a suitable clutch 42, and when connected to the shaft by said clutch will drive said shaft and hence the cutting mechanisms. The clutch is provided so that the cutting mechanism may be operated at will and any suitable or desired means may be employed for shifting the clutch 42. Rising from the frame 10 on each side of the chute A is a pair of arms 45 which are bridged or spanned at their upper ends above the chute by a bridge member or beam 46. The two arms 45 and the bridge 46 thus constitute an open frame which embraces or surrounds a chute A and this frame carries the upper cutting mechanism D which is disposed at substantially right angles to the planes of operation of the side cutters B. This cutting mechanism D lies close to the upper side or wall 2 of the chute 8 and it is preferably curved on an arc concentric with the arc of curvature of the chute A so as to be parallel to said wall 2. The forward end of this cutting mechanism extends a little beyond the side cutters B and the rear end of said cutting mechanism D is attached to the loop frame which embodies the arms 45 and bridge member 46 and which will be herein-after referred to by the letter E. The frame 50 of the cutting mechanism D is preferably in the form of an elongated curved plate, around the perimeter of which an endless cutting chain 51 travels. At the forward corners of the frame 50 are sprocket wheels 52, around which the chain passes. These sprockets are for the purpose of taking the thrust on the cutting chain and at the same time rendering the chain free running at these points. The chain may be of any suitable construction for the purpose.

In the construction shown (Figs. 1, 8 and 9) the chain is composed of a plurality of links 53, alternate links having outstanding holders 54 for the cutting blades or bits 55. Each of these holders has an angularly disposed socket for the reception of the shanks of the cutting bits 55 so as to hold said cutting bits at an angle. Alternate cutting bits on the chain are inclined or disposed in the same direction. They are removably held in their sockets by means of set screws 56. The chain runs on the perimeter or edge of the frame plate 50 in a groove formed by extending a portion 50^a of the frame beyond the main edge portion. This chain cutter is covered in my co-pending application Serial No. 860,371, filed September 5, 1914, and No. 12,760 filed March 8, 1915, and No. 848,726 filed July 3, 1914. This construction holds the chain against lateral movement in one direction with respect to the frame 50. Lateral movement of the chain in the other direction is prevented by forming the bit holders 54 with overhanging portions 57 which are adapted to run in a groove 58 formed in the extreme outer edge of the extension portion 50^a of same frame 50, as shown in Figs. 8 and 9. The extension portion 50^a is formed flush, so to speak, with the under or inner face of the frame 50, hence it provides in a sense a shelf or ridge on which the chain runs or travels. By this construction it is readily seen that the chain cannot become accidentally displaced with respect to the frame.

Depending from the under side of the bridge member 46 of loop frame E are two hangers 60 (Figs. 1, 3 and 4), in the form of shafts and these hangers are connected, at their lower ends, to a cross beam or member 61, which may be integral with the member 46, and the central portion of which is offset, as clearly shown in Fig. 4, to provide a groove or channel. In this channel fits the inner or rear end of the frame 50 which is reduced in width so as to fit said groove or channel. This structure is for the purpose of permitting the frame to be shifted to lengthen or tighten the chain. The offset portion of the bridge member 61 has a pair of slots 62 through which the bolts 63 pass, thus providing means for clamping the frame to the bridge member 61 and at the same time allowing for its adjustment relative thereto. The reduced end of the frame 50 has an upstanding lug 64 (Fig. 3) which passes through a central slot 65 in the offset portion of bridge member 61, and the offset portion of bridge member 61 also has an upstanding lug 66 aligned with the lug 65. An adjusting bolt 67 passes through both of these lugs by means of which the tightening or loosening of the chain may be accomplished. The shafts 60 carry sprocket wheels 68 around which the chain 51 passes and through the medium of one of which the chain is driven. One of these sprockets 68 has a bevel gear 69 formed therewith and this gear is connected with a corresponding gear 70 on a short transverse shaft 71. This shaft 71 is driven from a vertical shaft 72 through the medium of a pair of bevel gears 73 (Fig. 4). The shaft 72 extends upward along one side of the chute and adjacent one of the arms 45 of the frame E. At its lower end this shaft carries a bevel gear 74 which is driven by a corresponding gear 75 on a short transverse shaft journaled in the bearing 76 of the under side of the frame 10. This latter shaft is driven from the main shaft 34 (Fig. 2) by means of the intermeshing bevel gears 77. By means of the shafts and gears just described power is transmitted from the main shaft 34 to the upper cutting chain or mechanism D. From the foregoing it will be seen that the plate D is in the form of a segment of a cylinder, since its surfaces are parallel spaced-apart segmental cylindrical surfaces. The cutter chain 51 travels around the perimeter of the cutter frame D to form a curved kerf cutter which is capable of cutting a kerf of substantial width and of a thickness which is narrow compared with the width of the plate and which is only slightly greater than the thickness of the plate, thus reducing the cuttings to a minimum while providing sufficient clearance for free movement of the plate in feeding

direction. By such segmental cylindrical chain kerf cutter when fed into a mine wall on the center of the curvature of the plate or cutter frame D a segmental cylindrical kerf may be produced of substantial width and comparatively narrow in thickness."

As before mentioned the frame 10 and the cutting mechanisms D and B carried thereby are adapted to be bodily shifted in an arcuate path to feed said cutting mechanisms forward and to withdraw them. Referring to Figs. 3 and 4, it will be seen that at the lower edges of the side walls 1 of the chute or receiving structure A, are ribs or flanges 80 (Figs. 4 and 5) which form guides and supports for the bodily shiftable frame 10, the frame 10 being provided with curved grooves or channels 81 slidably fitting the ribs or flanges 80. The motor pinion 40 drives another large gear 82 which is keyed on a shaft 83 mounted in suitable bearings on the under side of the frame 10. This shaft carries a pinion 84 which is adapted to be connected with or disconnected from the shaft by means of a clutch 85 (Fig. 2). When connected with the shaft 83 the pinion 84 drives a gear 86 on another shaft 87 journaled in suitable bearings on the frame 10. This shaft 87 carries a worm 88 at one end, which drives a worm gear 89 on a transverse shaft 90. The transverse shaft 90 has a gear 91 at each end which meshes with and is adapted to travel along a curved toothed rack 92 positioned at the lower or under edge of each side wall of the chute A (Figs. 3, 4 and 5). This driving mechanism which I have just described is adapted to feed the frame 10 and hence the cutting mechanisms B and D forward for their cutting stroke. This forward or cutting stroke must necessarily be at a comparatively slow speed but the return stroke, during which the block of coal is removed by the cutting mechanism, as fully described in my aforesaid co-pending application, Serial No. 849,071, may be made at a quicker speed and I have provided mechanism therefore by which this quick return may be accomplished. The clutch 85 is a two-way clutch, having a neutral position, and is adapted also to be shifted to connect an internally toothed gear 93 which is normally loose on the shaft 83. This internally toothed gear drives a pinion 94 on the end of shaft 87 and rotates said shaft in the opposite direction and at a greater speed for the return stroke. It is understood, of course, that the clutch 85 may be shifted to connect either the pinion 84 or the internal gear 93 with the shaft but not both of them at the same time. Said clutch may also be shifted to an intermediate or neutral position so that neither of said gears will be connected with the shaft, as clearly shown

in Fig. 2. In my aforesaid copending application I have described, claimed and shown mechanism by which the chute may be clear of blocks of coal at the end of a 5 run or at any other time desired, and have provided mechanism for imparting a quick forward stroke to the cutting mechanisms for this purpose. In the present machine I have also provided means by which this may 10 be accomplished. I provide a gear 95 on the shaft 83 which gear is adapted to be connected with or disconnected from said shaft by means of the clutch 96. This gear when connected to said shaft drives a pinion 97 on a shaft 98 journaled in bearings on said frame 10 and carrying another pinion 99 which meshes with and drives the internal gear 93. These gears are proportioned to drive the frame 10 at a greater speed for 15 ward than the speed required on the cutting stroke thereof. In Figs. 10, 11 and 12 I have illustrated a modification of the structure previously described, this modification being adapted for the cutting of a plurality 20 (in this case two) of blocks of coal simultaneously. In this construction I provide a chute or receiving structure A of substantially twice the width of the chute in the previous views, this chute having a common 25 or intermediate middle wall A¹. This modified structure is built up by combining two single constructions like that shown in the preceding views, those parts and mechanisms which can be made common to the one 30 duplex machine being so constructed. If two single machines, such as previously described were placed side by side, there would be two side cutters adjacent each other which 35 would operate to cut too wide a kerf and in consequence I provide a middle or intermediate cutter B¹ common to both chutes, thus the modified construction has three vertical 40 kerf cutters instead of four. The construction of the frames, such as the frames 7 and 45 10, are widened accordingly.

The mounting of the side cutter B and B¹ are identical to that described in connection with the previous single machines, except that the shaft 17 is proportionately lengthened so as to be common to all three cutting 50 mechanisms. The cutting mechanisms D, however, are each constructed substantially as previously described but they are differently mounted because arranged in cylindrical 55 alignment with each other and in spaced apart relation so as to cooperate with the three vertical spaced apart cutters. Only one driving mechanism for the several sets of cutting mechanisms is necessary. In 60 other words, the driving mechanism previously described will serve equally as well for the duplex machine shown in Figs. 10 to 12, as it will for the single machine previously described, except that another shaft 65 100, driven through the gear 101 from the

shaft on which the bevel gear 77 is mounted, must be added. This shaft 100 extends to the opposite side of the structure where it drives another vertical shaft 102 through the medium of the bevel gears 103. The 70 shaft 102 is operated in the same manner as the shaft 72 previously described, and this shaft 102 in turn drives the additional cutting mechanism D in the same manner that the shaft 72 drives its cutting mechanism. 75 Beneath the intermediate wall A¹ of the chute there is an intermediate rack 92 and an additional gear meshing therewith on the shaft 90. In the modified construction in Figs. 10 to 12 the reference numerals and 80 letters are the same as used in connection with the previous single machine and no confusion will arise. It will be obvious that the machine may be constructed to simultaneously cut any number of blocks of 85 coal desired, but in the drawings I have shown how the mechanism should be constructed and arranged to cut an additional block simultaneously.

Referring to Figs. 13 to 21, it will be seen that the arcuate chute A is provided with a cylindrical portion 109 at the delivery end of the chute. This cylindrical frame 109 is provided with a circular flange 113 to abut 90 against the forward cylindrical portion 110 95 of the main supporting frame 108, when the cylinder 109 is inserted into the cylindrical bearing 110. The cylindrical frame 109 may be retained in the cylindrical bearing 110 by means of a retaining ring 112 between which 100 and the frame 110 may be interposed a gasket 111.

Mounted on the frame 109 outside of the chute but near the delivery end thereof, as 105 shown in Fig. 13, is an electric motor 114 on the shaft 115 of which is mounted a worm 116 meshing with the worm gear 117. The latter is keyed to a shaft 118 mounted in bearings fixed to the frame 109. On the shaft 118 is a spur gear 119 which meshes 110 with an internal gear 120, as shown more clearly in Fig. 9. It will thus be seen that when the motor 114 is operated in one direction or the other, the frame 109 together with the chute A will be rotated on a horizontal axis located at the center of the cylindrical bearing 110, the apparatus being locked in position by the worm gearing when the motor stops.

Extending forwardly from the frame 109 120 are spaced-apart guides 121, 121'. Between these guides is located a frame 122 which is provided with spaced-apart grooves 123, 123' fitting the guides 121, 121'. The frame 122 is provided with a cross piece 124 125 through which is threaded a bolt 125. This bolt also extends through a bracket 126 which is secured to the frame 109. Nuts 127 and 128 may be used for adjusting the position of the frame 122 relatively to the frame 130

109 and securing the frame 122 in adjusted position.

Pivoted to the frame 122 at 129 is an additional frame 130 which is provided with a longitudinal guideway for the kerf-cutting mechanism comprising the frame 131. On the latter a motor 132 is mounted in position to drive the under cutting kerf-cutter 133 through the gears 134, 135, 137, 138 and 139.

10 By referring to Fig. 15, it will be seen that provision is made for a slow forward feed of the kerf-cutter and a rapid retraction thereof and that the retraction is effected automatically when the kerf-cutter reaches the limit of its stroke. When the latter is in its initial position the operator may throw the clutch 140 to the left by moving the lever 142 to the right on the pivot 143, the clutch 140 being splined to the shaft 141 so as to rotate therewith. By moving the clutch 140 to the right which may be done by moving the lever 142 on the pivot 143, the gear 144 will be rotated and thereby transmit motion to a transverse shaft 145 through the spur gear 146 and the worm gears 147 and 148. At the ends of the transverse shaft are spur gears 149 which mesh with the spaced-apart racks 150. The clutch 140 is splined to the shaft 141 to rotate therewith.

When the under-cutting kerf-cutter 133 reaches the limit of its movement, the extension 142' of the clutch operating lever will engage the abutment 151 and move the clutch 140 to the left until motion is transmitted to the internal gear 136 with which meshes a gear to the left of the bearing 152 on the shaft 153. The transverse shaft 145 will thus be rotated in the opposite direction and more rapidly to secure quick retraction of the kerf-cutter whenever desired.

Connected rigidly to the frame 130 is a brake sector 154 which is provided with a brake surface 155 having the shape of the segment of a cylinder. Applied to this brake surface is a brake shoe 156 mounted on the brackets 157 and 158 of the frame 122. The brake shoe 156 is applied by the spring 159 and may be released manually by means of the lever 160 pivoted at 161. An abutment 162 is provided to limit the forward movement of the brake sector 154 and thereby also limit the downward movement of the undercutting kerf-cutter when the core-cutter is in the position shown in Fig. 13.

On the shaft 129 on the end opposite the brake sector 154 is a downwardly extending arm 163 which is pivoted to a piston rod 164 connected to a piston 165 in the dash pot 166 which is pivoted at 167 to the frame 122.

From the foregoing it will be seen that when the machine is operated as illustrated in Fig. 13, an arcuate core may be cut approximately radial from the center of the

upright mine wall toward the floor, roof or either of the side walls, and that whatever the position of the core may be, the kerf-cutter can operate to cut off the end of the core at the mine wall. The kerf may also be operated in various other positions by holding the brake applied. After the core has been cut completely from the unmined mass by means of the core-cutting mechanism and the plane kerf cutter, the latch 168, as shown in Figs. 13 and 14, will automatically engage the catch 169 so that when the core-cutter is retracted along the chute, the plane kerf-cutter will be moved with the kerf-cutter, as illustrated in Fig. 14. When the core-cutter reaches the position adjacent the receiving end of the chute, as shown in Fig. 14, the latch lever 170 will engage the cam 171 so as to automatically release the latch so that the plane kerf-cutter may return to its initial position. If the parts are in the position shown in Figs. 13 and 14, the plane kerf-cutter will return by gravity slowly because retarded by the brake mechanism.

It should be particularly noted that in my copending application, Serial No. 849,071, filed July 6, 1914, for a mining machine, I have described and claimed the plane kerf-cutting mechanism above illustrated and described and also the combination thereof with core-cutting mechanism; in said copending application I have also described and claimed the mechanism above described for rotarily mounting the core-cutting mechanism on an approximately horizontal axis. The present application embodies an improvement over said copending application in that instead of using an endless loop chain core-cutter having an unobstructed core-opening therethrough, I have shown and described spaced-apart plane kerf-cutters spanned by a kerf-cutter which has the shape of the segment of a cylinder and which is capable of cutting a corresponding arcuate kerf. An additional improvement over said copending application is the multiple core-cutting mechanism shown in Figs. 10, 11 and 12 and embodying three spaced-apart plane kerf-cutters and two arcuate kerf-cutters arranged in lateral or cylindrical alinement, as shown in Fig. 12. By means of this arrangement, only one intermediate plane kerf-cutter is necessary and the cores are separated only by a single kerf which is sufficient to effect movement of the cores into adjacent compartments of the multiple chute. This arrangement also makes the machine compact and enables it to cut adjacent cores simultaneously in a mine wall in a comparatively narrow entry or room in a mine.

It will be obvious to one skilled in the art after having obtained an understanding of my invention from the disclosures herein

made, that my invention may be modified without departing from the scope and spirit of the invention and I wish it so understood.

I claim:

5. 1. The combination with a frame, of a curved receiving chute carried thereby, a pair of cutting mechanisms on said frame for cutting side kerfs, an additional cutting mechanism supported by said frame and curved to conform to the curvature of the said chute, and means for operating said additional cutting mechanism to cut a kerf intersecting the kerfs cut by said pair of side kerf-cutting mechanisms. 70
10. 2. The combination of a curved receiving chute, disposed on an arc, side cutting mechanisms spaced apart and positioned on opposite sides of said chute, and means for bodily moving said side cutting mechanisms 75
20. relative to said chute and on the arcuate line on which said chute is disposed. 80
3. The combination of a receiving chute, disposed on an arc, side cutting mechanisms spaced apart and positioned on opposite 85
25. sides of said chute, means for bodily moving said side cutting mechanisms on the arcuate line on which said chute is disposed, and an outer cutting mechanism curved on an arc concentric with the arc of said chute, and 90
30. means for bodily feeding said outer cutting mechanism in the line of its curvature. 95
4. The combination of an arc-shaped receiving structure, a cutting mechanism curved to the arc of curvature of said receiving structure and adapted to be bodily reciprocated relatively to said receiving structure and on the arcuate line of its curvature, side cutting mechanisms spaced apart and adapted to cut a kerf intersecting the 100
40. kerf cut by said curved mechanism, and means for bodily moving said side cutting mechanism. 105
5. The combination of an arc-shaped receiving structure, a cutting mechanism curved to the arc of curvature of said receiving structure and adapted to be bodily reciprocated on the arcuate line of its curvature, side cutting mechanisms spaced apart and adapted to cut a kerf intersecting the 110
45. kerf cut by said curved mechanism, means for bodily moving said side cutting mechanism, and means for rotarily adjusting said side cutting mechanisms to vary their angle of operation. 115
55. 6. The combination of an arc shaped chute, a frame embracing said chute, means for reciprocating said frame on a curved line conforming to the curvature of the chute, a cutting mechanism supported by said frame and curved to the curvature of the chute, and a pair of side cutting mechanisms disposed at the sides of said chute beyond the 120
60. end thereof and mounted upon said frame. 125
7. The combination of an arc shaped chute, a frame embracing said chute, means 130
- for reciprocating said frame on a curved line conforming to the curvature of the chute, a cutting mechanism supported by said frame and curved to the curvature of the chute, and a pair of side cutting mechanisms adjustably mounted on said frame and bodily movable therewith, and means for rotarily adjusting said side cutting mechanisms to vary their angle of operation.
8. The combination of an arc shaped chute, a cutting mechanism embodying a curved frame conforming to the arc of curvature of said chute, and a cutting chain traveling around the perimeter of said curved frame, a pair of side cutting mechanisms spaced apart and operable in planes at an angle with respect to the plane of said first mentioned cutting mechanism, and means for bodily moving said cutting mechanisms.
9. The combination of an arc shaped chute, a cutting mechanism embodying a curved frame conforming to the arc of curvature of said chute, and a cutting chain traveling around the perimeter of said curved frame, a pair of side cutting mechanisms spaced apart and operable in planes at an angle with respect to the plane of said first mentioned cutting mechanism, a main frame supporting said first mentioned cutting mechanism, a sub-frame for said side cutting mechanisms adjustably mounted on said main frame, and means for reciprocating said frames and cutting mechanisms bodily, on an arc conforming to the arc of curvature of the chute. 100
10. The combination of an arc shaped chute, a cutting mechanism embodying a curved frame conforming to the arc of curvature of said chute, and a cutting chain traveling around the perimeter of said curved frame, a pair of side cutting mechanisms spaced apart and operable in planes at an angle with respect to the plane of said first mentioned cutting mechanism, a frame supporting said first mentioned cutting mechanism, a sub-frame for said side cutting mechanisms adjustably mounted on said plane, means for reciprocating said frame and cutting mechanism bodily on an arc conforming to the arc of curvature of the chute, and means for rotarily adjusting said side cutting mechanisms to vary their angle of operation. 110
11. In a mining machine, the combination with an elongated cutting mechanism curved in the line of its feed, of a curved frame on which said cutting mechanism is mounted for relative bodily movement, and means for rotarily adjusting said cutting mechanism with respect to said frame and in the line of its feed. 120
12. The combination of a curved supporting frame, an elongated cutting mechanism embodying a curved supporting frame and 130

a chain traveling around the perimeter thereof, means for adjusting said curved supporting frame longitudinally, and means for rotarily adjusting said cutting mechanism with respect to the frame, and means for driving said cutting chain.

13. The combination of a receiving chute disposed on an arc, a pair of cutting mechanisms bodily reciprocable and curved to conform to the curvature of said chute, a pair of side cutting mechanisms disposed adjacent the outer edges of said first-mentioned cutting mechanisms, and an intermediate cutting mechanism positioned midway of said side cutting mechanisms and disposed parallel with said side cutting mechanisms.

14. The combination of a receiving chute disposed on an arc, a pair of cutting mechanisms bodily reciprocable and curved to conform to the curvature of said chute, a pair of side cutting mechanisms disposed adjacent the outer edges of said first-mentioned cutting mechanisms, an intermediate cutting mechanism positioned midway of said side cutting mechanisms and disposed parallel with said side cutting mechanisms, and means for bodily actuating all of said cutting mechanisms to simultaneously sever a plurality of blocks from the vein of coal.

15. In a mining machine the combination of parallel arcuate chutes mounted in position for receiving blocks of material directly from their positions in the mine wall, and means for cutting closely adjacent cores of material in the mine wall and respectively in arcuate alignment with the chutes.

16. In a mining machine, the combination with a supporting frame, of a multiple chute in position on said frame to receive adjacent solid blocks of material directly from their positions in a mine wall, and multiple core cutting mechanism mounted on said frame in position for cutting adjacent cores of material in a mine wall, each core spaced from the open receiving end of one of the chutes and in alignment therewith directly in front of the receiving end of such chute.

17. In a mining machine, the combination with a receiving chute, of spaced apart plane kerf cutters in front of the receiving end of said chute, mechanism for guiding said kerf cutters along a path of travel to and from the receiving end of said chute at the sides of a space in alignment with said chute, and means for operating said kerf cutters including the bodily feed thereof along such path of travel to cut a body of material between said kerf cutters and in alignment with said chute.

18. In a mining machine, the combination with a receiving chute, of side cutting mechanisms spaced apart and associated with opposite sides of said chute, means for guiding said cutting mechanisms along paths of travel approximately in alignment

with the sides of said chute, and means for operating said cutting mechanisms including bodily feeding movement relatively to said chute to cut the material in alignment with said chute.

70

19. In a mining machine, the combination with a receiving chute, of side cutting mechanisms spaced apart in front of the opposite sides of said chute, an outer cutting mechanism spanning the space between said cutting mechanisms to inclose a space for the cut body of material in alignment with said chute, mechanism for guiding said side cutting mechanisms and said outer cutting mechanism in paths of travel to cut a body of material in alignment with said chute, and means for operating said cutting mechanisms including the feed thereof to cut a core of material in a mine wall in alignment with said chute for movement into said chute while being maintained intact.

75

20. In a mining machine, the combination with a supporting frame, of multiple receiving structure mounted thereon, multiple core cutting mechanism mounted at one end of said receiving structure, means for guiding said core cutting mechanism along paths of travel inclosing adjacent spaces respectively in alignment with the chutes, and means for operating said core cutting mechanism including feeding thereof along such paths of travel to cut adjacent cores of material in a mine wall in one feeding operation and respectively in alignment with said chutes.

80

21. In a mining machine, the combination with a supporting frame, of a receiving structure mounted thereon and having adjacent parallel chutes, multiple core cutting mechanism for cutting adjacent cores respectively in alignment with said chutes, means for guiding said core cutting mechanism back and forth in approximate alignment with said receiving structure, means for operating said core cutting mechanism to cut in one operation adjacent cores of material each in alignment with one of such chutes, and means for bodily moving said core cutting mechanism relatively to said receiving structure in a direction opposite to the feeding direction.

85

22. In a mining machine, the combination with a main frame, of a supplemental frame mounted for arcuate feeding movement on said main frame, plane kerf cutting mechanism mounted on said supplemental frame and extending approximately radially relative to the center of the arcuate feeding movement of said supplemental frame, means for operating said cutting mechanism including arcuate feeding movement thereof on said main frame along an arcuate path of travel to cut a plane kerf in a mine wall, an additional kerf cutter comprising a cutter frame having the shape of a segment of a cylinder

- and mounted in position to cut an annular kerf adjacent said plane kerf, and means for operating said additional kerfcutter. 65
23. In a mining machine, the combination with a main frame, of a supplemental frame mounted on said main frame for arcuate feeding movement thereon while deriving its sole support from said main frame, all the parts of said supplemental frame being movable along arcuate paths of travel spaced from the center of curvature of such paths of travel, plane kerfcutting mechanism comprising a traveling chain cutter, said plane kerfcutting mechanism being mounted on said supplemental frame for rotary adjustment relative thereto, means for holding said kerfcutting mechanism in adjusted position on said supplemental frame, a segmental cylindrical kerfcutter mounted on said supplemental frame concentrically of said center of curvature adjacent said plane kerfcutting mechanism, and means for operating said plane kerfcutting mechanism and said annular kerfcutter, including the feed of said supplemental frame along such arcuate path of travel while separated entirely from the center of curvature of such path of travel, to cut a plane kerf and an adjacent annular kerf in a mine wall. 70
24. In a mining machine, the combination with a main frame, of a supplemental frame movably mounted on said main frame, core cutting mechanism comprising spaced-apart plane kerfcutters and an intermediate segmental cylindrical kerfcutter mounted on such supplemental frame for rotary adjustment relative to said main frame, means for holding said core cutting mechanism in adjusted position, and means for operating such core cutting mechanism to cut an arcuate core in a mine wall. 75
25. In a mining machine, the combination with an elongated endless chain plane kerfcutter comprising a flat cutter bar, of a main supporting frame, a supplemental frame supported wholly by said main frame for an arcuate path of travel along said main frame spaced from the center of curvature and disconnected therefrom, means for supporting said chaincutter on said supplemental frame for arcuate adjustment relative to said supplemental frame, a segmental cylindrical kerfcutter mounted on said supplemental frame concentrically of said center of curvature, means for operating both of said kerfcutters, and means for holding said first-named kerfcutter in adjusted position without interfering with said operating means. 80
26. In a mining machine, the combination with a supporting frame, of spaced apart plane kerfcutters, each comprising an elongated frame and an endless chaincutter travelling around the same, a cross piece connected between said elongated frames, means for adjusting the position of said cross piece relatively to said supporting frame to effect adjustments of said kerfcutting mechanism relatively to said supporting frame, and means for operating said kerfcutting mechanism including the feed thereof, to cut parallel spaced apart kerfs in a mine wall simultaneously. 85
27. In a mining machine, the combination with a plurality of spaced-apart plane kerfcutters, of a frame having a flat cross piece for supporting said kerfcutters in spaced-apart parallel planes each substantially at right angles to the plane of said cross piece, a depending perforated lug connected to said crosspiece, means coacting with said lug for adjusting the positions of said kerfcutters relative to said frame, and means for operating said kerfcutters. 90
28. In a mining machine, the combination with a frame having a crosspiece, of an auxiliary frame also having a crosspiece engaging said first-named crosspiece so that the said crosspieces will be located in parallel planes, kerfcutting mechanism mounted on said auxiliary frame in position to cut a kerf in a plane at right angles to said crosspieces, means for operating said kerfcutting mechanism, and means for adjusting the relative positions of said crosspieces to effect a rectilinear adjustment of said kerfcutting mechanism. 95
29. In a mining machine, the combination with adjacent receiving chutes, of kerfcutting mechanism at the open receiving ends of said chutes, a main frame for supporting said chutes, a supplemental frame, means for feeding said supplemental frame along said main frame, an auxiliary frame carrying said kerfcutting mechanism and mounted on said supplemental frame, means for adjusting the position of said auxiliary frame relative to said supplemental frame to effect an adjustment of said kerfcutting mechanism in substantial alignment with the respective chutes, and means mounted on said supplemental frame and said auxiliary frame for operating said kerfcutting mechanism to cut adjacent cores respectively in alignment to said chutes. 100
30. In a mining machine, the combination with juxtaposed receiving chutes, of a main frame for carrying said chute, a supplemental frame, means for feeding said supplemental frame along said main frame, an auxiliary frame, multiple core cutting mechanism having adjacent unobstructed core openings respectively in alignment with said receiving chutes, means for securing said corecutting mechanism to said supplemental frame for rotary adjustment relative thereto, and means mounted on said supplemental and auxiliary frames for op- 105
- 110
- 115
- 120
- 125

erating said corecutting mechanism to cut adjacent cores for transfer to the respective chutes.

31. In a mining machine, the combination with a plurality of adjacent chutes, of a frame supported entirely by said chutes and movable relatively thereto, means for reciprocating said frame along said chute, a plurality of separate kerfcutting devices supported by said frame in position to cut separate adjacent bodies of material each in alignment with one of said chutes respectively, and means for operating said kerfcutting devices including the feeding thereof by movement of said frames along said chute while said frame and said kerfcutting devices are supported wholly by said chute.
32. In a mining machine, the combination with a supporting frame having a chute, of a supplemental frame movable along said chute while occupying a position adjacent thereto, means for controlling the reciprocation of said supplemental frame along said chute, cutting mechanism supported by said supplemental frame in position to cut a body of material in alignment with said chute, side cutting mechanism movable parallel to the sides of said chute, and means for operating said cutting mechanisms to cut a core of material in alignment with said chute.
33. In a mining machine, the combination with a receiving chute, of a kerf cutter comprising a cutter bar having the shape of a segment of an annulus with an endless chain cutter mounted on the perimeter thereof, means for driving said chain cutter around said cutter bar, and means for feeding said kerf cutter to cut a body of material in alignment with said chute.
34. In a mining machine, the combination with a receiving chute, of a main frame for carrying said chute, a supplemental frame movable relatively to said chute, kerf cutting mechanism comprising a cutter bar with an endless chain cutter mounted on the perimeter thereof, said cutter bar being in parallelism to said chute, and means for adjusting the position of said kerf cutting mechanism relatively to the open receiving end of said chute.
35. In a mining machine, the combination with a chute, of a frame movable relatively to said chute and longitudinally thereof, cutting mechanism supported by said frame for movement in parallelism to said chute and beyond the open end thereof, a pair of spaced apart side cutting mechanisms, and means for operating said cutting mechanisms including the feed thereof relatively to said chute and beyond the open end thereof to cut a core of material in alignment with said chute.
36. In a mining machine, the combination

with a chute, of cutting mechanism embodying a frame conforming to the shape of said chute, a cutting chain travelling around the perimeter of said frame, a pair of side cutters spaced apart and operable in planes at an angle with respect to the said first mentioned cutting mechanism, and means for operating the said cutting mechanisms including the bodily feed of said cutting chain and said side cutters.

37. In a mining machine, the combination with a main supporting frame, of a travelling frame mounted on said supporting frame for movement relatively thereto, a cutter frame connected to said travelling frame to move therewith, a chain cutter mounted on the perimeter of said cutter frame, side cutters mounted on said travelling frame for movement therewith, means mounted on said travelling frame for driving said chain cutter and said side cutters, and means for moving said travelling frame relatively to said supporting frame to effect feeding movement of said chain cutter and side cutters.

38. In a mining machine, the combination with an elongated cutting mechanism, of a travelling frame movable in a direction parallel to said cutting mechanism, means for adjusting the position of said cutting mechanism as a whole in the direction of its feeding movement and relatively to said travelling frame, side kerf cutters for cutting in parallel planes substantially at right angles to the said first named cutting mechanism, means for adjustably mounting said side cutters on said travelling frame, a main supporting frame, and means on said travelling frame for operating all of said cutting mechanisms including the feed thereof relatively to said main supporting frame into material in its native bed to cut a core therein.

39. In a mining machine, the combination, with a pair of spaced apart plane chain kerf cutters, of a main supporting frame, a travelling frame for carrying said kerf cutters, mechanism for guiding said travelling frame along said main frame in an arc to effect arcuate movement of said chain kerf cutters bodily, and means for operating said kerf cutters including arcuate feed of said travelling frame along said main frame to secure arcuate feed of all portions of said spaced apart kerf cutters from an initial cutting position intermediate the mine walls toward one of said walls.

40. In a mining machine, the combination with a main frame, of a supplemental frame, a plane kerf cutter mounted on said supplemental frame in fixed relation thereto for movement therewith along said main frame in an arc from an initial cutting position intermediate the mine walls toward

one of said walls, mechanism for guiding said supplemental frame along said main frame in an arcuate path of travel to secure arcuate feeding movement of said cutter bodily, and means for operating said kerf cutter including arcuate feed of all portions thereof by movement of said supplemental frame arcuately along said main frame to cut a kerf from such initial position toward one of said walls.

41. In a mining machine, the combination with a frame having the shape of a segment of an annulus, of a chain cutter mounted on the perimeter of said frame, a main frame, a supplemental frame carrying said first named frame and said chain cutter and movable in an arc concentric with the curvature of said first named frame, and means for operating said chain cutter including arcuate feed thereof on said main frame.

42. In a mining machine, the combination with a kerf cutting mechanism for producing a curved kerf in a mine wall, a pair of side plane kerf cutters disposed adjacent the outer edges of said curved kerf cutter, a supporting frame common to said curved kerf cutter and said side plane kerf cutters, a main frame, means for feeding said supporting frame in an arc on said main frame in accordance with the curvature of said curved kerf cutter, and means for actuating all of said kerf cutters.

43. In a mining machine, the combination with a receiving chute having inclosing walls, of separate side kerf cutters spaced-apart and on opposite sides of said chute in position to cut deep plane kerfs in a mine wall in advance of such chute, means for bodily moving said side kerf cutters on the line on which said chute is disposed to effect the feeding of said kerf cutters, an outer separate kerf cutter between said side kerf cutters and extending across one wall of said chute in position to cut an additional deep kerf into the mine wall in advance of said chute, and means for bodily feeding said outer separate kerf cutter in the mine wall.

44. In a mining machine, the combination with a receiving chute having enclosing walls, of separate side cutting mechanisms spaced apart and positioned on opposite sides of said chute, means for bodily moving said side cutting mechanisms on the line on which said chute is disposed, an outer separate cutting mechanism between said side cutting mechanisms and extending across one wall of said chute, and means for bodily feeding said separate cutting mechanisms in the line of said chute.

45. In a mining machine, the combination with a receiving structure having inclosing walls, of a stationary frame for supporting said receiving structure, a plurality

of separate plane kerfcutters movable bodily in feeding direction relatively to said receiving structure and at a mine wall in alignment with said receiving structure, and means for operating said separate plane kerfcutters to effect the cutting of deep kerfs into the mine wall in advance of said receiving structure.

46. In a mining machine, the combination with a chute, of a frame surrounding said chute, means for reciprocating said frame relatively to said chute on the line conforming to the direction of the chute, kerfcutting mechanism supported by said frame and extending in the same direction as said chute, and means for operating said kerfcutting mechanism to cut material at a mine wall beyond and in advance of the open end of said chute.

47. In a mining machine, the combination with a tubular chute having enclosing walls, of an open U-shaped frame extending around a portion of said chute, a cutter frame supported by said U-shaped frame and extending in the same direction as said chute, an endless chain cutter mounted on said cutter frame to travel around the perimeter thereof, means for driving said chain cutter, and means for moving said U-shaped frame and said cutter frame along said chute in a direction conforming to the direction of said chute to effect feeding movement of said chain cutter.

48. In a mining machine, the combination with a chute, of a frame extending around said chute, means comprising bearings on said chute for supporting and guiding said frame along said chute, cutting mechanism comprising a cutter frame carried by said first-named frame and movable therewith in the direction of said chute, and means for operating said cutting mechanism including feed thereof by moving said first-named frame along said bearings while the latter confine movement of both of said frames along parallel paths of travel.

49. In a mining machine, the combination with a pair of spaced apart kerf cutters, of a frame for carrying said kerf cutters, a tubular chute with its open end adapted to face the space between said cutters and adjacent thereto when in initial cutting position at a mine wall, and means for operating said cutters including the feed thereof by movement of said frame relatively to said chute to cut spaced apart kerfs in a body of material in a mine wall in alignment with said chute.

50. In a mining machine, the combination with a supporting frame, of a supplemental frame comprising a tubular chute and mounted on said supporting frame for rotation on an axis extending in a general horizontal direction, an additional frame movable relatively to the said supplemental

frame, a plurality of kerf cutters carried by said additional frame for operation beyond the open end of said chute to cut a body of material in alinement with said chute, and means for operating said cutting mechanism including the feed thereof by movement of said additional frame relatively to said chute.

51. In a mining machine, the combination with a main frame, of a supplemental frame movably mounted thereon, multiple core cutting mechanism mounted on said supplemental frame, and means for operating said core cutting mechanism to cut at 15 the back and sides of a body of material at an upright mine wall to form a plurality of cores of material extending transversely of the mine heading.

52. In a mining machine, the combination with supporting framework, of interconnecting kerf cutting mechanism, means for supporting said kerf cutting mechanism in position to cut cores extending transversely of the upright sides of the mine 25 wall operated on, and means for operating said cutting mechanism to cut a plurality of immediately adjacent cores in a mine wall in one operation, such cores extending transversely of the mine chamber.

53. In a mining machine, the combination with a plurality of spaced apart plane kerf cutters, of a frame for supporting said kerf cutters in parallelism as well as spaced apart from each other, a plurality of additional kerf cutters respectively spanning the adjacent spaces between the first named kerf cutters and means for operating all of said kerf cutters including the feed thereof to cut a plurality of immediately adjacent 35 cores of material in a mine wall.

54. In a mining machine, the combination with a supporting frame, of multiple core cutting mechanism mounted on said supporting frame, means for operating said 45 multiple core cutting mechanism to cut immediately adjacent cores in a mine wall, and a plurality of chutes mounted on said supporting frame and disposed respectively in alinement with the cores of material cut by 50 said multiple core cutting mechanism.

55. In a mining machine, the combination with a plurality of separate spaced-apart parallel plane kerf cutters each comprising a driving sprocket, of a shaft directly connecting said sprockets for concentric rotation with said shaft, a supporting frame, means for rotating said shaft and said sprockets to drive said kerf cutters, and means for swinging said separate kerf cutters relatively to said frame to feed the same 60 deeply into the mine wall to produce parallel spaced-apart kerfs each of a depth many times greater than the thickness of said kerfs.

56. In a mining machine, the combina-

tion with a plurality of elongated chain cutters each comprising a driving sprocket, a driving shaft common to said sprockets, means for turning said shaft to actuate said sprocket wheels, a frame for supporting said chain cutters in parallel spaced apart relation, additional kerf cutters spanning the space between each of said first named kerf cutters and the next adjacent kerf cutter, means for actuating said additional kerf 75 cutters, means for feeding all of said kerf cutters to cut a plurality of immediately adjacent cores in a mine wall, and a partitioned chute dividing the same into a plurality of compartments to respectively receive the cores cut by said kerf cutters.

57. In a mining machine, the combination with an open ended chute having enclosing walls and an intermediate dividing partition to form two longitudinal compartments in said chute, a frame surrounding said chute, lateral bearings on said chute for driving said frame along said chute, three spaced apart parallel elongated chain cutters respectively in alinement with the 80 side walls and the partition of said chute and supported by said surrounding frame, two additional kerf cutters carried by said frame in alinement with each other laterally outside of said chute and respectively spanning the space between the intermediate elongated kerf cutter and an outer elongated kerf cutter, and means for operating all of said kerf cutters including the feed thereof to effect the cutting of cores immediately 85 adjacent each other and respectively in alinement with the compartments of said chute.

58. In mining apparatus, the combination with a plurality of separate spaced-apart plane kerfcutters, a framework for supporting said kerfcutters for swinging feeding movement in position to enter the mine wall transversely thereof between the floor and roof of a mine chamber while initially spaced from such floor and roof, and means for operating said kerfcutters including such swinging feed thereof to cut 95 blocks of material in a mine wall.

59. In a mining machine, the combination with a receiving structure, cutting mechanism comprising a plurality of separate angularly disposed kerfcutters, means for operating said cutting mechanism including the feed thereof to cut a plurality of intersecting kerfs including a kerf spaced back 115 from the face of the mine wall to form a block of material transversely of the mass being mined and directly in alignment with said receiving structure, and framework for supporting said receiving structure and said cutting mechanism in co-operative relation during the operation of said cutting mechanism.

60. In a mining machine, the combination with a supporting frame, of a receiving 130

chute disposed on an arc and extending substantially from the forward to the rear end of said frame, core cutting mechanism comprising two spaced apart plane kerf cutters and a separate intermediate kerf cutter operable adjacent the forward end of said chute and bodily movable in an arc the center of which is coincident with the center of the arc of said chute, and means for operating said core cutting mechanism to cut a core on its forward stroke in the mass of material being mined and in arcuate alignment with said chute.

61. In a mining machine, the combination with cutting mechanism curved in the line of its feed and comprising a curved cutter frame having segmental cylindrical surfaces, a supporting frame for said cutting mechanism, and means for operating said cutting mechanism including arcuate feed thereof along the line of curvature of said frame.

62. In a mining machine, the combination with a supporting frame, of a kerf cutter mounted thereon and having the shape of a segment of an annulus, and means for operating said kerf cutter including the feed thereof relatively to said supporting frame.

63. In a mining machine, the combination with a main frame, of a kerf cutter having the shape of a segment of an annulus and comprising a cutter frame with a chain cutter mounted on the perimeter thereof, mechanism comprising a supplemental frame for carrying said kerf cutter and guiding the same relatively to said main frame along an arc concentric with the curvature of said kerf cutter, and means for operating said kerf cutter including arcuate feed thereof on said main frame.

64. In a mining machine, the combination with a main frame, of kerfcutting mechanism comprising a cutter bar having the shape of a segment of a cylinder, said cutting mechanism being mounted on said main frame in position to cut a curved incision in the mine wall, means for guiding said cutting mechanism along said main frame over an arcuate path of travel, and means for operating said cutting mechanism including feed thereof along such said path of travel in accordance with the curvature of said cutter bar to effect the cutting of a curved incision in a mine wall.

65. In a mining machine, the combination with a supporting frame, of segmental cylindrical cutting mechanism thereon in position to cut an arcuate incision into the body of material at a mine wall, and means for operating said cutting mechanism including the feed thereof in arcuate alignment with said cutting mechanism deeply into the mine wall.

66. In a mining machine, the combination with a supporting frame, of segmental cy-

lindrical cutting mechanism mounted thereon in position to cut a curved incision deeply into the body of a mine wall in arcuate alignment with said cutting mechanism, mechanism for confining movement of said cutting mechanism to such arcuate feed and against movement of said cutting mechanism parallel to the axis of arcuate feed, and means for operating said cutting mechanism including arcuate feed thereof while being thus confined to cutting ahead of said annular cutting mechanism and in arcuate alignment therewith.

67. In a mining machine, the combination with a supporting frame, of kerfcutting mechanism comprising a cutter frame having the shape of a segment of a cylinder, said kerfcutting mechanism being mounted on said frame in position to cut a curved kerf in a mine wall extending into the body thereof from the face thereof, mechanism for confining the path of travel of said kerfcutting mechanism to lines extending along said segment, and means for operating said kerfcutting mechanism including such feed thereof.

68. In a mining machine, the combination with a supporting frame, of kerfcutting mechanism comprising an arcuately curved frame with a chain cutter mounted on the perimeter thereof, means for driving said chain cutter, and means for feeding said curved frame in accordance with the curvature thereof to effect the cutting of a curved kerf in advance of said curved kerf cutter frame.

69. In a mining machine, the combination with cutting mechanism comprising a curved frame with a chain cutter mounted on the perimeter thereof, of means for supporting said cutting mechanism for feeding movement on an axis spaced from said cutting mechanism, and means for operating said cutting mechanism including feed thereof to cut a curved incision in the material to be mined.

70. In a mining machine, the combination with kerf cutting mechanism having the shape of a segment of an annulus and comprising an endless chain cutter, of means for supporting said kerf cutter in position to cut a curved kerf in a mine wall, and means for operating said kerf cutter including arcuate feed thereof.

71. In a mining machine, the combination with a main frame, of a supplemental frame, curved kerf cutting mechanism mounted on said supplemental frame, means for adjusting said kerf cutter circumferentially, and means for operating said kerf cutter including arcuate movement of said supplemental frame to secure feeding movement of said kerf cutter on an axis spaced from said kerf cutter.

72. In a mining machine, the combination with a supporting frame, of kerf-cutting mechanism comprising a cutter frame having the shape of a segment of a cylinder with an endless chain cutter mounted on the perimeter thereof, a supplemental frame mounted on said supporting frame and carrying said segmental cylindrical kerf cutter, mechanism for confining the movement of said segmental cylindrical kerf cutter relative to said supporting frame to lines of feeding travel in parallelism to cut an arcuate kerf in advance of said kerf cutter and in arcuate alinement therewith, and means for operating said kerf cutter by driving said chain cutter and feeding said supplemental frame arcuately relatively to said supporting frame to cut such arcuate kerf.

73. In a mining machine, the combination with a main frame, of a supplemental frame mounted thereon for arcuate movement relatively thereto, curved cutting mechanism mounted on said supplemental frame for arcuate movement therewith to cut a kerf having a center of curvature on an axis spaced therefrom and substantially parallel thereto, said curved cutting mechanism comprising a curved cutter frame and a chain cutter mounted thereon to travel around the same, and means for operating said cutting mechanism to cut a kerf in arcuate alinement therewith.

74. In a mining machine, the combination with kerf-cutting mechanism comprising a cutter frame having the shape of a segment of a cylinder with an endless chain mounted on the perimeter thereof, and means for operating said cutting mechanism to cut an annular incision in a mine wall in arcuate alignment with said cutting mechanism and in advance thereof.

75. In a mining machine, the combination with spaced-apart parallel kerf cutters, of supporting frame-work therefor, a curved kerf cutter of substantial width and comparatively narrow in thickness and mounted in position to cut a kerf of substantial width and of the thickness of said kerf cutter, means for supporting said kerf cutter for operation between the parallel spaced-apart kerfs, and means for operating said spaced-apart kerf cutters and said curved kerf cutter to cut an arcuate core of material in a mine wall.

76. In a mining machine, the combination with a supporting frame, of kerf-cutting mechanism mounted thereon for cutting spaced-apart kerfs, a curved kerf cutter comparatively narrow in thickness and having the shape of a segment of a cylinder and mounted in position to cut an arcuate kerf spanning said spaced-apart kerfs, and means for operating said kerf cutters to cut a core of material in a mine wall,

77. In a mining machine, the combination with supporting framework, of kerf-cutting mechanism mounted in position to cut spaced-apart kerfs, an additional kerf cutter mounted in position to cut a back curved kerf, said additional kerf cutter being of substantial width and comparatively narrow in thickness to have the shape of a segment of a cylinder, and means for operating said kerf-cutting mechanism and said additional kerf cutter to cut such spaced-apart kerfs and a curved kerf about a body of material in a mine wall.

78. In a mining machine, the combination with a supporting frame, of a supplemental frame mounted for arcuate movement on said supporting frame, spaced-apart elongated chain kerf cutters extending radially relatively to the axis of arcuate movement of said supplemental frame, an additional elongated kerf cutter mounted on said supplemental frame and extending arcuately relative to such axis in position to cut a curved back kerf at the outer ends of said spaced-apart kerf cutters, and means for operating said spaced-apart kerf cutters and said additional elongated kerf cutter including feed thereof on said axis to cut an arcuate core in a mine wall.

79. In a mining machine, the combination with a supporting frame, of an arcuate chute mounted thereon, a kerf cutter having the shape of a segment of an annulus, and means for operating said kerf cutter to cut an arcuate kerf in arcuate alinement with one of the walls of said chute.

80. In a mining machine, the combination with a receiving chute, of spaced-apart chain kerf cutters in position to cut spaced-apart kerfs in arcuate alinement with the respective side walls of said chute, a curved chain kerf cutter mounted in position to cut a curved kerf in arcuate alinement with an intermediate wall of said chute and between said side kerfs, mechanism for guiding said side kerf cutters and said curved chain kerf cutter along arcuate paths of travel to effect the cutting of a body of material in a mine wall, and means for operating said kerf-cutting mechanism including the feed thereof to cut a core of material in a mine wall in alinement with said chute.

81. In a mining machine, the combination with a main frame, of a supplemental frame mounted for arcuate feeding movement on said main frame, kerf cutting mechanism mounted on said supplemental frame and extending approximately radially relatively to the axis of the arcuate feeding movement of said supplemental frame, additional kerf cutting mechanism extending circumferentially relatively to such axis, and means for operating said kerf cutting mechanism and said additional cutting

mechanism including arcuate feeding movement on such axis.

82. In a mining machine, the combination with an arcuate chute, of a main frame for supporting said chute, a supplemental frame supported entirely by said chute and movable arcuately along the same, kerf cutting mechanism comprising a cutter bar having the shape of a segment of an annulus and supported by said supplemental frame in position to cut a body of material in arcuate alignment with said chute, and means for operating said kerf cutting mechanism including arcuate feeding thereof by arcuate movement of said supplemental frame along said chute while said supplemental frame and said cutting mechanism are supported wholly by said chute.

83. In a mining machine, the combination with a supporting frame having an arcuate chute, of a supplemental frame supported by said chute and movable arcuately along the same, spaced apart side kerf cutters mounted on said supplemental frame in position to cut spaced apart kerfs approximately in alignment with the inner lateral walls of said chute, a curved kerf cutter mounted on said supplemental frame in position to cut an interconnecting kerf in arcuate alignment with an intermediate inner wall of said chute, and means for operating said kerf cutters including arcuate feed thereof by movement of said supplemental frame arcuately relatively to said chute to cut a body of material in arcuate alignment with said chute.

84. In a mining machine, the combination with a supporting frame, of multiple core-cutting mechanism having adjacent unobstructed core openings therethrough and mounted on said frame in position to cut immediately adjacent cores in a mine wall, and means for operating said multiple core-cutting mechanism including the feed thereof to cut immediately adjacent cores to extend through said unobstructed core openings.

85. In a mining machine, the combination with multiple chain cutting mechanism, of means for supporting said chain cutting mechanism to form adjacent unobstructed core openings, means for operating said cutting mechanism to cut an E-shaped kerf in a mine wall and form adjacent cores bounded by such kerfs and the face of the mine wall, and framework for supporting the aforesaid structure in position for operation on material in its native bed.

86. In a mining machine, the combination with a supporting frame, of multiple curved core cutting mechanism having adjacent unobstructed curved core openings extending therethrough, said core cutting mechanism being mounted on said frame in position to

cut communicating U-shape kerfs in a mine wall projecting through such unobstructed core openings, and means for operating said multiple core cutting mechanism to cut such kerfs to produce curved cores extending through such openings.

87. In a mining machine, the combination with three spaced apart plane kerf cutters, of two annular kerf cutters in transverse alignment with each other for spanning the spaces between each plane kerf cutter and the next adjacent kerf cutter, means for supporting said plane kerf cutters and said annular kerf cutters to form adjacent unobstructed core openings, and means for operating said kerf cutters including the feed thereof to cut adjacent arcuate cores separated by the kerf produced by the intermediate plane kerf cutter.

88. In a mining machine, the combination with supporting framework, of multiple loop core cutting mechanism each section having an unobstructed core opening therethrough, said core cutting mechanism being mounted on said framework in position to entirely sever from the mine wall a plurality of immediately adjacent arcuate cores extending through such unobstructed core openings, and means for operating said multiple core cutting mechanism to produce such cores.

89. In a mining machine, the combination with a supporting frame, of a supplemental frame rotatively mounted thereon, a multiple core cutter having adjacent unobstructed core openings therethrough, said cutter being mounted on said supplemental frame to move bodily therewith, and means for operating said multiple core cutter to produce adjacent cores respectively extending through said unobstructed core openings.

90. In a mining machine, the combination with a supporting frame, of a plurality of spaced apart kerf cutters comprising intermediate and outer kerf cutters, a plurality of spaced apart additional kerf cutters mounted on said supporting frame in a predetermined relation to said spaced apart kerf cutters to cooperate therewith to cut adjacent cores of material and means for simultaneously operating said first-named spaced apart kerf cutters and said additional kerf cutters to cut such adjacent cores.

91. In a mining machine, the combination with supporting framework, of a multiple core cutter having closely adjacent unobstructed core openings extending therethrough, means for operating said multiple core cutter to cut three spaced apart kerfs extending into the mine wall from the face thereof and communicating back kerfs spaced back from the face of the mine wall

to produce closely adjacent cores extending through the respective core openings, and means for adjusting the multiple core cutter relatively to said framework to vary 5 its position of operation.

92. In a mining machine, the combination with supporting framework, of spaced apart plane kerf cutters, an intermediate plane kerf cutter, additional kerf cutters 10 for spanning the spaces between the intermediate kerf cutter and the outer kerf cutters, and means for operating all of said kerf cutters to effect the cutting of adjacent cores with the kerf formed by the intermediate kerf cutter the division between the 15 cores.

93. In a mining machine, the combination with multiple curved core-cutting mechanism having adjacent unobstructed curved 20 core openings therethrough, a multiple curved chute having receiving ends respectively in arcuate alinement with said unobstructed curved core openings, and means for operating said curved core-cutting 25 mechanism to cut adjacent curved cores respectively in alinement with the curved chutes of said multiple chute.

94. In a mining machine, the combination of supporting framework, and an arcuate 30 multiple chute mounted thereon having independent but closely adjacent arcuate passageways.

95. In a mining machine, the combination of supporting framework and a curved multiple chute mounted thereon comprising an intermediate partition for dividing the chute into closely adjacent parallel curved passageways.

96. In a mining machine, the combination 40 with supporting framework, of a plurality of parallel tubular chutes mounted thereon, means for adjusting the position of said chutes relatively to said framework, kerf cutting mechanism mounted in position to 45 cut kerfs approximately in alinement with three of the walls of each of the tubular chutes, and means for operating said kerf cutting mechanism to cut cores of material respectively in alinement with the parallel 50 tubular chutes.

97. A mining machine comprising kerf-cutting mechanism having a cutter frame with surfaces of the shape of segments of a cylinder.

98. A mining machine comprising a cutter frame having arcuate spaced-apart surfaces in the shape of segments of concentric cylindrical surfaces.

99. A mining machine comprising a cutter 60 frame having approximately the same thickness throughout, a cutter thereon, means for driving the cutter, and mechanism for feeding the frame arcuately longitudinally of itself during the driving of said cutter

to cut a narrow kerf only slightly greater 65 in thickness than the thickness of said frame.

100. A mining machine comprising a supporting frame, an arcuate kerf cutter mounted thereon, and means for operating said kerf cutter to cut a kerf having the shape of 70 the segment of a cylinder.

101. A mining machine comprising a curved cutter frame, cutting means thereon, and means for moving said cutter frame to effect the cutting of material to form a wall 75 extending along straight lines transversely of the cutter frame.

102. A mining machine comprising a cutter frame arranged along straight lines transversely thereof and along curved lines longitudinally thereof, cutting means on 80 said cutter frame, and means for moving the cutter frame to effect the cutting of material along lines corresponding to those of the said cutter frame.

103. A mining machine comprising a cutter frame arcuate longitudinally thereof and rectilinear transversely thereof, a chain cutter mounted on the perimeter of said cutter frame, means for driving said chain cutter, and means for moving said cutter frame in the direction of its curvature to feed said chain cutter while being driven to effect the cutting of a kerf arcuate longitudinally 85 thereof and rectilinear transversely thereof.

104. In a mining machine, the combination with a multiple tubular receiver into which cut material is adapted to be passed, said receiver having adjacent inlet openings at one end, core-cutting mechanism associated with the said inlet openings, and means for supporting said core-cutting mechanism in position to cut cores in arcuate alinement with said tubular receiver.

105. In a mining machine, the combination with a swinging multiple receiver, of open cutting components adapted to cut material in columns directly from a mine vein, and means for cutting such columns of material in alinement with the said receiver 110 in the various positions to which it may be swung.

106. In a mining machine, the combination with an arcuate chute mounted in position for receiving blocks of material directly from the positions in the mine wall, of spaced-apart plane kerf cutters, an intermediate curved kerf cutter, and means for supporting said kerf cutters in position to cut an arcuate core in arcuate alinement with 115 said chute.

107. In a mining machine, the combination with a chute, of kerf-cutting mechanism comprising a plane kerf cutter and a curved kerf cutter, and means for operating said kerf cutters to cut a body of material from a mine vein in position to be received by 120 said chute.

108. In a mining machine, the combination with a receiver having adjacent inlet openings, of cutting components movably associated with said receiver to cut coal in 5 columns from the face of a mine vein and cause the coal to be directed into said inlet openings, and means for operating such cutting component.

109. In a mining machine, the combination with a multiple receiver, of cutting mechanism comprising a frame adapted to form an extension of such receiver, and means for operating said cutting mechanism to dislodge material from a mine vein 15 and direct such material in parallel columns along such cutter frame into said multiple receiver.

110. In a mining machine, the combination with a multiple receiver having cutting 20 components movably associated therewith to cut material in parallel columns from the face of a mine vein and cause such material as it is cut to be passed directly into and carried clear of the vein by the receiver 25 and said component, and means for operating the cutting component.

111. In a mining machine, the combination with a plurality of parallel curved chutes, of core-cutting mechanism in position 30 to cut a plurality of parallel cores in arcuate alinement respectively with said chutes, and curved extensions for said chutes to direct the cores into said chutes.

112. In a mining machine, the combination with an arcuate receiving chute, of core-cutting mechanism comprising spaced apart plane kerf cutters and an intermediate curved kerf cutter having a curved cutter frame, means for supporting said core-cutting 35 mechanism in position to cut a core in arcuate alinement with said arcuate chute and so that said curved frame will form an extension of said chute, and means for operating said core-cutting mechanism.

113. In a mining machine, the combination with supporting framework, of a multiple core cutter each section having an unobstructed core-opening therethrough, means for supporting said multiple core cutter on 50 said frame work for feeding movement relatively thereto, and means for operating said multiple core cutter including feeding movement thereof relatively to said framework to simultaneously cut adjacent cores respectively extending through the unobstructed core-openings of said sections.

114. In a mining machine, the combination with a supporting frame, of cutting mechanism having adjacent unobstructed 60 core-openings extending therethrough, means for supporting said cutting mechanism on said frame for arcuate feeding movement relatively thereto, means for driving said cutting mechanism, and means for swinging 65 said cutting mechanism relatively to effect the dislodgment of a crescent-shaped mass of material.

said frame to effect arcuate feeding movement of said cutting mechanism to cut arcuate juxtaposed cores while said frame remains stationary.

115. In a mining machine, the combination with a supporting frame, of multiple core-cutting mechanism comprising a plurality of chain kerf cutters, means for supporting said multiple core-cutting mechanism on said frame in position to cut juxtaposed cores in a mine wall, means for driving said core-cutting mechanism, and mechanism for feeding said core-cutting mechanism in an arc relatively to said frame to simultaneously cut a plurality of arcuate juxtaposed cores in the mine wall while said frame remains stationary.

116. In a mining machine, the combination with means for cutting two spaced-apart plane kerfs across a mine wall, of a 85 separate single arcuate kerf-cutter for cutting a kerf at or near the inner ends of the plane kerfs and between the same, and means for operating said plane kerf-cutters and said arcuate kerf-cutter to cut a single core 90 of material.

117. In a mining machine, the combination with spaced-apart plane kerf-cutters, of an arcuate kerf-cutter comprising a frame of sector-cylindrical shape and an endless chain-cutter mounted on the periphery thereof, and means for operating said kerf-cutters including the feed thereof.

118. In a mining machine, the combination with kerf-cutting mechanism comprising means for cutting spaced-apart plane kerfs, of a frame for supporting said kerf-cutting mechanism, operating means for said kerf-cutting mechanism, and an arcuate kerf-cutter detachably connected to said operating means and comprising a sector-cylindrical frame with a chain-cutter thereon, and mounted for operation at or near the inner ends of the kerfs produced by said kerf-cutting mechanism and between such kerfs.

119. In a mining machine, the combination with spaced-apart plane kerf-cutters, of means for supporting said kerf-cutters for arcuate feeding movement, an upright arcuate kerf-cutter mounted on said supporting means for operation at or near the inner ends of said plane kerf-cutters and between the same, said arcuate kerf-cutter comprising a forwardly extending curved frame with a chain-cutter thereon, and means for operating said plane kerf-cutters and said upright kerf-cutter including arcuate feed thereof to effect the dislodgment of a crescent-shaped mass of material.

120. In a mining machine, a cutter-head comprising a pair of vertically spaced kerf-cutters pivotally connected with said frame, means for swinging said cutter-head laterally to cause said cutters to form upper and lower horizontally extending kerfs, and an

upright cutter curved to conform to the curvature of the arc described by the outer portions of said spaced cutters, and means for supporting said upright cutter in position to form a kerf substantially in vertical alinement with the outer edges of the kerfs formed by said spaced cutters.

121. In a mining machine, the combination with a cutter-frame having the shape of 10 a segment of an annulus, of an endless chain-cutter mounted to travel around the perimeter of the annular cutter-frame, and

means for supporting said cutter-frame for arcuate swinging movement on an upright axis.

15

In testimony whereof I have signed my name to this specification, in the presence of two subscribing witnesses, on this third day of July A. D. 1914.

EDMUND C. MORGAN.
